WRAPPING ARTICLE

Walter Everett Molins, deceased, late of Deptford, London, England, by Harold Bernardo Molins, Deptford, London, England, and Moses Hyman Isaacs, London, England, executors, assignors to Molins Machine Company, Limited, London, England.

Application March 23, 1936, Serial No. 70,520
In Great Britain April 8, 1935

8 Claims.

(Cl. 93—2)

This invention is for improvements in or relating to wrapping articles. Where herein and in the appended claims the term "length" or "lengthwise" is applied to the wrapping material or to the articles to be wrapped, it refers to "length considered in the direction of movement of the part referred to whilst the wrapping material is being folded into an open-ended tubular wrapper".

According to one form of the present invention there is provided a method of wrapping articles which comprises bringing the articles into contact with wrapping material (e. g., a web from a reel or severed lengths) the length of the wrapping material in all cases being arranged to extend beyond the leading and rear ends of the articles, moving the articles together with the wrapping material and during such movement forming the wrapping material into tubular form about the articles, the throughway of the tube being in the direction of movement, and if necessary securing the seam (e. g., by adhesive), severing the wrapping material between successive articles in the case where there is not a previously cut portion of wrapping material for each article, and closing (e. g., by folding or twisting) the open ends of the tubular wrappers. The articles may be placed at substantially equally spaced intervals along a length of continuous wrapping material, or the articles may be moved into engagement with wrapper blanks and disposed relatively thereto in a manner such that the blanks extend beyond the ends of the articles.

Further according to the invention there is provided a machine for wrapping articles comprising means to move an article and wrapping material (e. g., a length of material greater than the length of the article) into engagement with each other, means to move the article and wrapping material in a lengthwise direction, means to form the wrapping material during such movement into an open ended tubular wrapper about the articles with the axis of the tube lying in the direction of movement and when the length of wrapping material is greater than that of the article, means to close the open ends of the wrapper. Conveyor means may be provided to grip the wrapping material and to move it past folding elements which co-operate with the conveyor to fold the wrapping material about the articles. The conveyor may comprise an endless band or bands.

The conveyor may comprise a plurality of bands, at least one of which is arranged as a movable support for the wrapping material and arti-

cles to be wrapped, the other said bands co-operating with folding elements to fold or partly fold the wrapping material about the articles. The conveyor may comprise a band or bands having a surface of rubber or other material having properties similar to rubber. Means may be provided and movable in timed relationship with the wrapping material to position the articles relatively thereto. The positioning means may be operative to engage with an article until the wrapper is at least partly folded about the article.

The invention will be described by way of example with reference to the accompanying drawings, in which:

Figure 1 is a plan of a machine constructed in accordance with the invention.

Figure 2 is an end elevation of Figure 1 in the direction of the arrow 2, Figure 1.

Figure 3 is a sectional elevation on line 3—3, Figure 1.

Figure 4 is a sectional elevation on line 4—4, Figure 1.

Figures 5 to 13 inclusive illustrates various stages during the formation of a wrapper about an article, the arrows indicating the direction of movement of the article and wrapper during the folding of the wrapper about the article.

Like references refer to like parts throughout the specification and drawings.

Referring to Figures 1 to 13, the articles to be wrapped are enclosed in blanks of wrapping material. Wrapper blanks 30 are severed by knives 31 and 32 from a continuous web 33 of wrapping material fed from a reel, not shown. The blanks severed from the continuous web 33, are received between endless bands 34 and 35, which are rubber bands or composite bands the blank engaging surfaces of which are rubber or have properties similar to that of rubber. The bands 34 and 35 are arranged as shown in Figure 1, from which it will be seen that the bands are arranged in two pairs which are spaced apart and engage with the wrapper blank at spaces adjacent the longitudinal edges thereof. The bands 34 and 35 carry the wrapper blank past an adhesive applying device which comprises a roller or disc 36, arranged to receive adhesive from a roller 37 rotating in an adhesive bath 38. The adhesive applying roller or disc 36 is arranged to apply a line of adhesive 39 as shown in Figure 5, the line of adhesive being adjacent one longitudinal edge of the wrapper blank 30 and extending along the whole length of the wrapper blank (see Figure 5).

After the adhesive has been applied to the wrapper blank, the blank is carried by the bands 34 and 35 to a position at which it is moved in a horizontal path and is received by a conveyor which in the machine being described comprises an endless band 39 having a blank receiving surface similar to that of the bands 34 and 35 (i. e., a rubber or like surface) and which moves between the two pairs of bands 34 and 35. In the machine being described, the wrapping material is material such as that which is sold under the registered trade-mark "Cellophane", and it is found that such material adheres to a rubber surface in a manner such that it is firmly gripped thereby and is not easily displaceable thereon.

Articles 40 to be wrapped are carried from any suitable source (not shown) by an endless band 41, the articles being moved as a column, as shown in Figure 1. The leading packet of the column is arrested by a stop 42, and is then engaged by a pusher piece 43 carried by an endless conveyor 44. The endless conveyor 44 comprises two chains, the sprockets for which are arranged as shown in Figure 3, and each pusher piece 43 is pivotally mounted on plates 45 secured to the chains. By reason of the arrangement of the pusher pieces relatively to the conveyor, the pusher pieces are at the beginning and end of their operative path moved through a vertical path and into and out of engagement with an article. The pusher pieces 43 are moved in timed relationship with the speed at which the wrapper blanks 30 are fed to the band 39 and are arranged to position an article upon a wrapper blank as shown in Figure 5, so that the wrapper blank extends lengthwise beyond the leading and rear ends of the article.

The conveyor 39 conveys the wrapper blank and article lengthwise between twisted bands 46 and 47, which fold the wrapper blank into a U-shape about the article, as shown in Figure 6. Whilst the wrapper blank is being folded by the bands 46 and 47, the article is still controlled by means of the pusher piece 43, and this pusher piece continues to control the article until just before the article and wrapper blank are moved between folding elements 48 and 49, which fold the upstanding limbs of the U into engagement with

each other, as shown in Figure 8, to form a seam. Figure 7 illustrates the wrapper as though one limb were completely folded into engagement with the article before the folding operations are commenced upon the other limb. In some cases, the folding may be effected in this manner, but in the machine shown in Figure 1, the folded portion shown in Figure 7 is folded slightly in advance of the upstanding limb shown in Figure 7, the folders for this purpose being constructed as spiral folding elements of the usual known type and operating to fold the upstanding limbs of the wrapping material downwardly about the support 51, which support facilitates the downward folding of the upstanding portions and also has a further function which is referred to below. The seam formed as shown in Figure 8 is secured by means of the line of adhesive 39.

After passing between the twisted bands 46 and 47, the articles and wrappers are carried by the band 39 between two further endless bands 50 and 51 which move at the same speed as that at which the band 39 is moving, and which are arranged to grip the sides of the partly wrapped articles. The tension of the belts 50 and 51 may be adjusted by means of jockey rollers 52 and 53, the spindles of which are movable in slots 54 and 55. When the bands 50 and 51 have been adjusted, the spindles of the rollers 52 and 53 are clamped in position.

When the wrapper has been folded so that it forms an open ended tube about the article, the ends of the tubular wrapper extend beyond the leading and rear ends of the article as shown in Figure 8, and the partly wrapped articles are carried beneath a heating element 56, which presses upon the seam of each wrapper and dries the adhesive by means of which the seam is secured. It will be seen that those portions of the tube which extend beyond the ends of the article are unsupported, and in order to provide means whereby the whole of the seam of the tubular wrapper may be dried and secured, a thin plate 57 is provided. The plate 57 rests on the tops of the articles being wrapped before the upstanding limbs of the U are folded into engagement with each other and extends along the whole of the length of the heating element 56, and is supported by the successive articles being moved by the band 39 so that the heating element presses the seams of the successive wrappers against the bar 57. By this means those portions of the wrappers which extend beyond the leading and rear ends of the articles are dried and secured.

The bands 39, 50 and 51 deliver the partly wrapped articles on to a stationary plate 58, and rotatable gripping members 59 and 60 are arranged to grip the articles as they leave the bands and move the partly wrapped articles against stops 61 and 62. The stops 61 and 62 are pivoted at 63 and 64 respectively, and are connected with links 65 and 66 which are in turn connected with one arm of the bell crank lever 67. The other arm of the bell crank lever carries the cam follower 68 which engages with a cam 69. The ends of the stop 61 and 62 which engage with the partly wrapped articles are provided with lips 70 and 71 (see Figure 3), and these lips engage with the end of the article to effect the location thereof and also serve to partly fold the open end of the tubular wrapper. As the article is brought into position to be arrested by the stops 61 and 62, the stops are turned about their pivots 63 and 64 until they assume the position shown in Figure 3, and locate the partly wrapped article. The links 75

65 and 66 are slotted at those ends which engage with the stops 61 and 62, and the ends of the stops 61 and 62 are provided with pins which engage with the slots in the links 65 and 66. The purpose of the slots in the links 65 and 66 is to provide a means of adjustment whereby the apparatus may be arranged to deal with articles of varying sizes. When the apparatus is set for a particular size of article to be wrapped, the stops 61 and 62 are secured relatively to the links 65 and 66.

When the partly wrapped article has been positioned by the stops 61 and 62, a plunger 72 (see Figure 4) operated by a cam 73 through the medium of a bell crank lever 74 moves the article transversely of the direction of movement in which it was moved whilst the wrapper blank 30 was folded into tubular form about the article, and the partly wrapped article is inserted by the plunger 72 into a magazine constituted by a fixed plate 75 and a resilient top member in the form of a brush 76. As each partly wrapped article is ejected by the plunger 72, the leading article in the magazine is moved into the path of one of the pusher pieces 77 carried by an endless conveyor 78, and the pusher piece conveys the partly wrapped article through 90° and places it upon the surface of the bed 79 of the machine. Whilst the article is being conveyed from the plate 75 and deposited on the bed 79 it is controlled by means of a guide 80, which is shown in the drawings as a brush.

When the stops 61 and 62 are moved out of engagement with the article, after positioning it to be engaged by the plunger 72, the partly folded end of the wrapper tends, due to the resiliency of the wrapping material, to assume substantially the tubular shape which the partly folded wrapper had before being engaged by the stops 61 and 62. As the pusher 77 moves the partly wrapped article along the bed 79, the open ends of the tubular wrapper are engaged first by stationary folders 81 and 82 which form the narrow end folds 83 (see Figure 10) at the ends of the wrapper, and then by rotating elements 84 and 85, which form the narrow ends 86 (see Figure 10). The folding of the narrow end folds 83 and 86 causes broad end flaps 87 and 88 to be formed, and in order thoroughly to crease the small triangular folds 89 which occur on both the broad flaps 87 and 88, the broad flaps 87 and 88 are passed between pressing rollers 90, 91, 92 and 93 (see Figure 4). The broad flaps 87 and 88 are folded upwardly as shown in Figure 11 by means of fixed folders 94 and 95, and the partly wrapped articles as shown in Figure 11 are moved past rotatable adhesive applying wheels 96 and 97, which receive adhesive from the discs 98 and 99, rotating in adhesive baths 100 and 101. The wheels 96 and 97 apply lines 102 of adhesive to the upstanding flaps 87, after which the pusher piece conveys the partly wrapped article between folders 103, which fold the upstanding flaps 87 downwardly into engagement with the flaps 88.

The line 102 of adhesive which is applied to the flap 87 does not extend to the edge of the flap 87, so that when the flap 87 is caused to engage the flap 88, the extreme end portion of the flap 87 is not secured to the flap 88. The unsecured end portion of the flap 87 provides a means by which the wrapper may be gripped when it is desired to open the wrapper, and in order to enable the free portion more readily to be gripped, it is bent upwardly as shown in Figure 13. A folding element 104 (see Figure 4) engages with

the free end portion of the flap 87, and folds the free end portion upwardly against the outer surface of the broad end flap 87. If desired, a printing or other ink applying device may be provided to apply colouring matter to the free end portion of the flaps 87 to make the free portion distinctive. The wrapped articles are thereafter delivered by the pusher pieces 77 to any suitable collating device, and the adhesive between the broad end flaps 87 and 88 may be dried by any of the well known heating elements, which may be caused to engage with the broad end flaps either before or after their insertion into the collating magazine.

It will be appreciated that instead of the wrapper blanks being of a length such that the tubular wrappers extend beyond the leading and rear ends of the articles being wrapped, they may be of a length equal to or shorter than the length of the article. In cases such as this the mechanism for closing the ends of the tubular wrappers will not be needed.

Referring to the modified construction shown in Figures 14 to 24, the wrapping material, instead of being cut into wrapper blanks, as was the case in the construction above described, is fed as a continuous web 33 from a reel 33a. The continuous web 33 is carried by an endless band 105 through folding mechanism described below, which folds the wrapping material into a continuous tubular wrapper about the articles to be wrapped.

The articles to be wrapped are stacked in a magazine 106, the magazine being inclined in the direction of movement of the continuous web of wrapping material, and the lowermost article in the magazine is supported as shown in Figure 16 by an inclined plate 107.

The article being supported by the plate 107 is moved into engagement with the travelling web of wrapping material by means of a plunger 108 which moves the article out of the magazine and the inclined plate 107 is shaped so that the article assumes an upright position on the continuous web of wrapping material, as shown in Figure 17. It will be seen that by this means the article is given a component of movement in the direction of movement of the web 33 of wrapping material before it is fully supported thereby, and the movement of the plunger is such that when the article is fully deposited upon the web 33, it is moving in the same direction as and at the same speed as the web 33. The web 33 carries the article between guides 109 and 110, and the web of wrapping material is folded into a U-shape about the articles by means of a series of pairs of slotted guides 111, 112, 113, which engage with the longitudinal edges of the web 33. Each successive pair of guides 111, 112, 113 is arranged more closely together than the preceding pair in order to form the wrapping material gradually into a U shape about the articles carried by the wrapping material.

The wrapping material is moved past an adhesive applying wheel 114, which receives adhesive from a disc 115 rotating in an adhesive bath 116, and the wheel 114 applies a line of adhesive along the whole length of the web of material and adjacent one longitudinal edge thereof as seen clearly in Figure 18. The band 105 and wrapping material 33 then carries the articles past the apparatus which is arranged to locate each successive article upon the wrapping material relatively to cutting mechanism, which will be described below, and which is arranged to

sever the continuous tubular wrapper at points substantially midway between successive articles contained therein. The locating device is indicated generally in Figure 14 by the reference 5 117, and is shown more clearly in Figure 19. A rotatable disc 118 is driven in timed relationship with the cut-off mechanism, and carries four pivoted fingers 119. Each finger 119 is provided with a cam follower 120, which engages with a 10 cam 121 fixed relatively to the disc 118. The fingers 119 are arranged to engage with the rear end of each article conveyed by the band 105 and web 33, and place the same in the desired position upon the wrapping material. Springs 15 122 are provided to control the fingers 119.

When the articles have been located upon the wrapping material 33, the band 105 together with the wrapping material 33 and the articles thereon are moved between folding elements 123 and 124 20 which fold the upstanding edges of the U formed by the wrapping material into engagement with the upper surfaces of the articles and into engagement with each other, so that the overlapping longitudinal edges of the wrapping material form the seam which is secured by the 25 line of adhesive above referred to. The folders 123 and 124 fold the wrapping material about a thin plate 57, which is provided for the purpose described above with reference to the construction shown in Figures 1 to 4 of the drawings. The tubular wrapper and the articles contained therein are thereafter moved beneath a heating element 56. After passing the heating element 56 which dries the adhesive securing the seam 30 of the wrapper, the tubular wrapper, together with the articles, is moved to cutting mechanism indicated generally in Figure 14 by the reference 125, which severs the continuous tube substantially midway between two successive articles, 35 as shown diagrammatically in Figure 24. The cutting mechanism comprises a ledger plate 126 having an aperture 127 through which the tubular wrapper and articles pass, the ledger plate 126 being carried on a bracket 128, which is mounted 40 on guides 129, 130, along which the bracket is arranged to slide. A link 131 is connected to the bracket 128, and the free end of the link is connected with a crank 132. The crank causes the ledger plate to move in the direction of movement 45 of the continuous tubular wrapper, during the cutting operation, and at the same speed as the speed at which the continuous tubular wrapper is moving, so that the knife 133 co-operates with the ledger plate during the severing of the tubular wrapper.

The knife 133 is shown in the drawings as a circular disc which is rotatably mounted on an arm 134, the arm 134 being pivoted about a spindle 135. The knife 133 is rotated about its axis by 50 a pulley 136, which is connected by a belt 137 to a driving pulley 138, slidably mounted on the spindle 135. The pulley 138 is restrained against rotary movement relatively to the spindle 135 by keys 139, and the boss of the pulley 138 is slotted 55 to accommodate the keys 139, and also extends through the arm 134, as can be seen in Figure 22.

During the cutting operation, the knife 133 has a complex movement, being moved transversely of the direction of movement of the continuous tubular wrapper in order to sever the wrapper, and also being given a component of movement in the direction of movement of the tubular wrapper, the knife being moved in the same direction as and at the same speed as that 60 at which the continuous wrapper tube is moving

during the severing of the tube. The movements imparted to the knife during the cutting operation are effected as follows:

The movement imparted to the knife in the direction of movement of the wrapper tube is 5 provided by means of a crank 140 to which is connected a link 141 secured to the arm 134. The crank causes the arm 134 and the driving pulleys for rotating the knife to reciprocate axially of the spindle 135. In order to move the 10 knife transversely of the direction of movement of the continuous wrapper, a cam 142 engages the cam follower 143 connected to one arm of a lever 144, which is pivoted at 145. The other arm of the lever is provided with a slotted guide 146 (see Figure 23) and a sliding block 147, connected with the arm 134, is located in this guide and causes the arm 134 to follow the movements of the lever 144. As the lever 144 is rocked about its pivot 145, the arm 134 is in 15 turn rocked about the spindle 135, the arm 134 being mounted as shown in Figure 22 so as to be free to oscillate on the boss of the pulley 138, and this movement causes the knife 133 to be moved transversely of the direction of movement 20 of the tubular wrapper.

When the continuous tubular wrapper is being severed by the knife 133, it is found that there is a tendency for the continuous wrapper to tear, and also for the articles to become displaced 25 slightly relatively one to the other. To reduce this tendency, there is provided on each side of the knife 133 a pair of rotatable rollers 148 and 149, the pair of rollers 148 being arranged to engage with the article on one side of the 30 knife 133, whilst the pair of rollers 149 is arranged to engage with the article on the other side of the knife 133 during the cutting operation which severs the tubular wrapper. The rollers 148 and 149 are moved with a slightly greater surface 35 speed than that at which the continuous wrapper and articles are being moved, so that the tubular wrapper is pulled taut. It will be seen that the rollers 148 and 149 are arranged to grip the 40 articles both during and after the severing operation, and that by this means the tubular wrapper is tautened during the cutting operation, and the articles within the tubular wrapper are controlled both before and after the cutting operation has been completed.

After the cutting operation has been completed, the severed length of tubular wrapper, together with the article contained therein, is gripped between a pair of co-operating belts 150 and 151, which move the tubular wrapper and article at a speed which is greater than the speed at which the continuous tubular wrapper is moving, and by this means the severed lengths of wrapping material and the articles contained therein are spaced apart in the direction of movement thereof. The bands 150 and 151 then deliver the partly wrapped articles to stops such as the stops 61 and 62, described above, and the tubular wrappers are thereafter closed in the manner above described with reference to Figures 1 to 4.

The construction described with reference to Figures 1 to 4, in which the tubular wrappers are formed from wrapper blanks is preferred to the construction shown in Figures 14 to 24, because in the construction shown in Figures 14 to 24, it is necessary when starting the machine to feed the continuous web of wrapping material through the machine before starting to operate the machine, and it is found that this is a some- 70 75

what cumbersome proceeding, due to the width of the material used and the length of the material which has to be fed through the machine before starting up the machine. With the machine shown in Figures 1 to 4, the machine when started up is entirely automatic, and the difficulty experienced with the machine described with reference to Figures 14 to 24 is avoided.

By means of machines constructed in accordance with the present invention it is possible to wrap articles in tubular wrappers at a very high speed, that is, speeds of between 500 and 1,000 per minute, and it is found that in some instances it is not possible to provide mechanism to close the open ends of the wrappers at this high speed. In such cases, instead of the open ended tubular wrappers containing articles being moved into one set of closing mechanism, there may be provided two sets of closing mechanism arranged for example side by side, and the open ended tubular wrappers, together with their articles, may be moved alternately to each of the closing mechanisms. In this way it will be seen that the closing mechanism need only operate at half the speed at which the mechanism for forming the tubular wrappers about the articles operates.

Such an arrangement is shown in Figures 25 and 26, wherein certain of the mechanisms previously described have been omitted to promote clarity of illustration. The plunger 72 (Figure 1) is replaced by a reciprocating ejector 160 which comprises a flat vertical plate having a downwardly extending arm to which is secured a slide 161. The latter is slidably mounted in a guide 162, and is provided with a pin 163 which slidably engages a slotted lever 164. The latter is pivoted to a suitable portion of the machine frame, as at 165, and carries a cam follower 166, for engagement with a cam 167, which latter is substituted for the cam 73 (Figure 4). A spring 168 maintains the cam follower 166 constantly in engagement with the cam 167. It will be obvious that the ejector 160 is thus reciprocated laterally, and is adapted to move a wrapped article to one side and then, upon its return, to move the succeeding wrapped article to the right, and so on.

The closing mechanism of Figure 4 is duplicated on either side of the ejector mechanism, as indicated in Figures 25 and 26, each closing mechanism being adapted to receive alternate wrapped articles from the advancing line of such articles, and to complete the closing operations as previously described.

What is claimed as the invention and desired to secure by Letters Patent is:—

1. In a machine for wrapping articles the combination with means to feed wrapping material, of means to deposit an article on the wrapping material, folding elements to fold the wrapping material into tubular form about the article, and a locating element movable in synchronism with the wrapping material and operative to engage the article, after the latter has been deposited on the wrapping material, to position the article relatively to the wrapping material.

2. In a machine for wrapping articles the combination with means to feed individual wrapper blanks, of means to deposit an article on a wrapper blank, folding elements to fold the wrapper blank into tubular form about the article, and a locating element movable in synchronism with the wrapper blank and operative to engage the article, after the latter has been deposited on the

wrapper blank, to position the article relatively to the wrapping material.

3. In a machine for wrapping articles the combination with means to feed wrapping material, of means to deposit an article on the wrapping material, folding elements to fold the wrapping material into tubular form about the article, and a locating element comprising an endless conveyor provided with an article engaging member movable in synchronism with the wrapping material and operative to engage the article, after the latter has been deposited on the wrapping material, to position the article relatively to the wrapping material.

4. In a machine for wrapping articles the combination with means to feed individual wrapper blanks, of means to deposit an article on a wrapper blank, folding elements to fold the wrapper blank into tubular form about the article, and a locating element comprising an endless conveyor provided with an article engaging member movable in synchronism with the wrapper blank and operative to engage the article, after the latter has been deposited on the wrapper blank, to position the article relatively to the wrapping material.

5. In a machine for wrapping articles the combination with means to feed wrapping material, of means to deposit an article on the wrapping material, folding elements to fold the wrapping material into tubular form about the article, a conveyor to receive the wrapping material and article, said conveyor being movable between said folding elements together with the wrapping material and article to be wrapped, and a locating element movable in synchronism with the wrapping material and operative to engage the article, after the latter has been deposited on the wrapping, to position the article relatively to the wrapping material.

6. In a machine for wrapping articles the combination with means to feed individual wrapper blanks, of means to deposit an article on a wrapper blank, folding elements to fold the wrapper blank into tubular form about the article, a conveyor to receive the wrapper blank and article, said conveyor being movable between said folding elements together with the wrapper blank and the article to be wrapped, and a locating element movable in synchronism with the wrapper blank and operative to engage the article, after the latter has been deposited on the wrapping, to position the article relatively to the wrapper blank.

7. In a machine for wrapping articles the combination with means to feed a continuous web of wrapping material, of means to deposit articles at intervals along the length of the web, folding elements to overlap opposed edges of the wrapping material to form a tubular wrapper about the articles, said overlapping portions being adhesively secured to form a seam for the wrapper, a support about which the opposed edges of the wrapper are folded while being overlapped, said support being disposed between the folding elements and the article, a cutting device to sever the tubular wrapper between successive articles whereby each article is contained in a tubular wrapper, and means to hold the tubular wrapper taut while it is being severed by said cutting device.

8. In a machine for wrapping articles the combination with means to feed a continuous web of wrapping material, of means to deposit articles at intervals along the length of the web, folding

elements to fold the wrapping material into tubular form about the articles, a cutting device to sever the tubular wrapper between successive articles whereby each article is contained in a tubular wrapper, means to hold the tubular wrapper taut while it is being severed by said cutting device, said last named means comprising movable endless surfaces arranged to engage the wrapping material and the articles between

which the cutting device is operative and to move at a greater surface speed than the speed at which the wrapper and articles are moved towards the cutting device.

HAROLD BERNARDO MOLINS,
MOSES HYMAN ISAACS,
*Executors of the Estate of Walter Everett Molins,
Deceased.*
